TRUMP INDICATOR FOR CARD GAME

Frank E. Peart, Rte. 1, Box 75, Camdenton, Mo. 65020

Filed Nov. 25, 1966, Ser. No. 4,807

Term of patent 14 years

(Cl. D34—13)

FIG. 2 is an end elevational view thereof;

FIG. 3 is an end elevational view thereof showing the end opposite that appearing in FIG. 2; and

FIG. 4 is a top plan view of the trump indicator for card game.

The broken lines indicate conventional card suites.

I claim:

The ornamental design for a trump indicator for card game, as shown and described.
